AUTOMATIC WINDOW SCREEN

Gaudenz Sgritta, Berkeley, Calif.

Application March 30, 1935, Serial No. 13,935

2 Claims. (Cl. 156—39)

My invention relates to improvements in automatic window screens and it consists of the combinations, constructions and arrangements hereinafter described and claimed.

5 An object of my invention is to provide an automatic window screen in which a roll-away screen may be attached to the upper sash of a window, and a second roll-away screen attached to the lower sash of the same window whereby the raising or lowering of the two sashes into open position will unwind the screens so that the screens will cover the opening provided. If desired the screens may be detached from the window sashes and then the window can be opened in the usual 10 manner.

Each screen is mounted upon a spring roller and has a stop or keeper secured to its free edge so that this stop will engage with the window frame when the screen is not attached to the window sash, and this will prevent the edge of the screen from disappearing into the window frame.

Novel means is provided for permitting one to gain access to either of the roll-away screens. 25 One of the principal objects of the invention is the provision of a spring-pressed bolt used for removably connecting the screens to the window sashes.

Other objects and advantages will appear in 30 the following specification, and the novel features of the device will be particularly pointed out in the appended claims.

My invention is illustrated in the accompanying drawing forming a part of this application, 35 in which

Figure 1 is a section along the line 1—1 of Figure 2;

Figure 2 is a section along the line 2—2 of Figure 1;

40 Figure 3 is an enlarged sectional view of the lower screen mechanism;

Figure 4 is an enlarged sectional view of the upper screen mechanism;

45 Figure 5 is a top plan view of the spring-pressed bolt; and

Figure 6 is a side elevation of Figure 5.

In carrying out my invention I make use of a window indicated generally at 1. The window structure has two wells 2 for receiving weights 3 50 that are connected to the lower sash 4 by ropes 5 in the usual manner. An upper sash 6 is movably mounted in the window frame, and the weights for balancing this sash are not shown in the drawing.

55 The top rail 7 of the window frame has a piece

8 that is removably secured in place by hinges 9 and 10, see Figure 1. This piece is secured in alignment with the top rail by means of the hinges, or other suitable fastening means. The piece 8 carries the upper roll-away screen. 5

The detail features of the upper screen are shown in Figure 4, and it will be noted that brackets 11 are mounted on the piece 8, and these brackets carry a spring-actuated roller 12 around which is wrapped a screen 13. When repairing 10 the roller 12 or screen 13, the portion of the hinge 9 or 10 secured to the vertical side of the window frame may be freed by removing the screws securing this portion to the frame. The piece 8 may now be swung downwardly about the 15 other hinge and will expose the roller and screen. The roller may now be removed from the brackets 11. The free edge of the screen receives a reinforcing channel 14, and this channel is secured to a stop or a keeper 15 which is Z-shaped 20 in cross section.

It will also be noted from Figure 4 that the top rail 16 of the upper sash 6 is provided with a groove 17 that is flared outwardly at 18 for receiving the lower edge of the keeper 15. The 25 keeper 15 is removably secured to the upper sash 6 by means of spring-pressed bolts indicated generally at 19.

Reference to Figures 5 and 6 show the detail 30 of the spring-pressed bolts 19. Each bolt comprises a casing 20 mounted upon a base 21, and receiving a plunger 22. A head 23 is secured to the top of the plunger 22 and a pin 24 projects radially from the plunger. The pin is slidably received in a bayonet slot 25, and a spring 26 35 urges the pin 24 down to the bottom of the slot.

Two of the spring-pressed bolts 19 are secured to the top rail 16 of the upper sash 6. The keeper 15 has openings 27 for receiving the plunger 22, and in this manner the screen 13 is removably 40 secured to the upper sash.

It will be noted that when it is desired to gain 45 access to the upper screen it is merely necessary to remove the screws securing the vertical hinge portions to the frame, and then to swing the piece 8 downwardly from the top rail. This will expose the brackets 11 and the spring roller 12.

The lower screen construction is shown in detail in Figure 3. A removable base 28 forms a 50 part of the window sill 29 and is removably held in place by two straps 30 which are secured to the base 28 and to the sill 29 by screws 31, or other suitable fastening means. Lag screws 41 pass through the sill 29 and are threaded into the base 28. The screws may be tightened for pull- 55

ing the abutting edges of the base and sill together for forming a water-tight joint. Brackets 32 are mounted on the base 28 and carry a spring-actuated roller 33 around which is wrapped a

5 screen 34. The free edge of the screen is mounted in a U-shaped clamp 35, and is removably received in a recess 36 in the bottom rail 37 of the lower sash 4. The U-shaped clamp 35 has an angular portion 40 underlying the rail 37, and 10 this portion projects beyond the rail 37 a slight distance, and acts as a weather strip to prevent the entrance of water beneath the lower sash.

Spring-actuated bolts 19 are used for removably securing the screen 34 to the lower sash, and 15 since the structure of these bolts is the same as that used for the upper sash, further description need not be given, except to say that the plungers 38 of the lower spring-pressed bolts 19 are shorter in length than those used on the upper bolts. 20 The lower bolts 19, when securing the screen 34 to the lower sash 4, will cause the screen to unwind from the roller 33 when the lower sash is raised. In this way the screen automatically covers the opening in the window as the lower 25 sash is raised.

When it is desired not to use either of the screens the bolts 19 may be retracted and held in retracted position by the pins 24 being received in the portions 39 of the bayonet slots 25. The 30 Z-shaped keeper 15 will prevent the upper screen from being pulled entirely within the compartment A which encloses the screen. In like manner, the portion 40 is secured to the lower screen and engages with the base 28 for preventing the 35 lower screen from being entirely received within the compartment B housing the lower screen.

The device is extremely simple in construction, and is durable and efficient for the purpose intended. It provides a ready means for covering 40 the window opening with a screen, and of entirely removing the screen when the window is closed.

While I have shown only the preferred form of my invention, it should be understood that various changes or modifications may be made with- 45 in the scope of the appended claims without departing from the spirit of the invention.

A wiper 42 is carried by the upper sash 6 and prevents insects from gaining entrance between the sashes when the sashes are opened.

I claim:

1. A window frame including a sill which is so 5 embodied in the frame as to partly define and cover a roller screen compartment, said sill having an opening which comes within the confines of the compartment, roller screen-carrying means comprising a base situated in the opening to complete the compartment but being narrower than the opening, brackets pendent from the base and a roller mounted on the brackets and having a screen wound thereon, means by which the base is attached to the sill so as to define a slot adjacent to the room side of the sill, the free end of the screen passing through the slot, means swiveled on the weather side of the sill and detachably connected to the adjacent side of the base by which to pull the confronting edges of the sill 10 and base into weather-tight abutment, and a sash guided by the frame to which sash the free end of the screen is attached.

2. A window frame including a sill which is so 15 embodied in the frame as to partly define and cover a roller screen compartment, said sill having an opening which comes within the confines of the compartment, roller screen-carrying means comprising a base situated in the opening to complete the compartment but being narrower than the opening, brackets pendent from the base and a roller mounted on the brackets and having a screen wound thereon, means by which the base is attached to the sill so as to define a slot adjacent to the room side of the sill, the free end of the screen passing through the slot, a screw 20 detachably swiveled on the weather side of the sill and being screw-threaded into the adjacent side of the base, the turning of the screw pulling the confronting edges of the sill into weather-tight abutment, and a sash guided by the frame to which sash the free end of the screen is attached.
